FULL VIEW RIFLE FRONT SIGHT

Oscar E. Forsling, Kimball, Nebr.

Application April 23, 1935, Serial No. 17,877

6 Claims. (Cl. 33—47)

This invention relates to a rifle front sight adapted to be used with a conventional peep rear sight.

It is particularly aimed to provide a construction which will enable the marksman to obtain a full view of the target through the sight so as to be not only more efficient generally, but a boon for marksmen whose eyesight is failing.

It is further aimed to provide a construction wherein different sights may be substituted as desired and wherein such sight will be held in an absolutely accurate position and a construction wherein continued use will not produce such wear between the parts as will effect the accurate positioning of the sight or a clear and open view.

The more specific objects and advantages will become apparent from a consideration of the description following taken in connection with accompanying drawing illustrating an operative embodiment.

In said drawing:—

Figure 1 is a view in side elevation illustrating my improvements applied to the barrel of a rifle, the latter being fragmentarily shown;

Figure 2 is an enlarged longitudinal sectional view through the improvement;

Figure 3 is a vertical sectional view taken on the line 3—3 of Figure 2;

Figure 4 is a vertical sectional view taken on the line 4—4 of Figure 2;

Figure 5 is a front elevation of one form of sight;

Figure 6 is a front elevation of a second form of sight;

Figure 7 is a cross sectional view taken on the line 7—7 of Figure 6;

Figure 8 is a front elevation of a third form of sight;

Figure 9 is a vertical sectional view taken on the line 9—9 of Figure 8; and

Figure 10 is a perspective view of the carrier.

Referring specifically to the drawing, 10 designates a mounting bracket provided with an attaching base 11 of dove-tailed cross section adapted to be slidably applied to the usual dovetail slot 12 in a part 13 of a rifle barrel 14.

Said bracket has a longitudinally disposed tube 15. Said tube and base are preferably integral, connected by a web or shank 16.

Removably slidable in the tube 15 and applicable from the front, is a tubular sight carrier member 17 which is preferably provided with an annular outwardly extending manipulating flange 18 at its forward end, the flange prefer-

ably being externally knurled as at 19 to facilitate manipulation. The forward portion of the web 16 is slotted or bifurcated as at 20 and receives a lug 21 integral with the tube 17 and depending therefrom. A set screw 22 is applied to the web 16 so as to bind against the lug 21, and it preferably has a knurled head 23 to facilitate finger manipulation.

The sight employed has a ring 24, the opening through which is of the same diameter throughout. However the ring has to the extent of 180 degrees, a thin or reduced portion 25 and for the remainder of its circumference has a wide or thicker portion 26. The difference in width of the portions 25 and 26 is the same as the thickness of the wall of the tubular carrier 17. Such carrier 17 has its wall radially slotted to the extent of 180 degrees at 27. As a result, the sight, when the carrier 17 is removed from the tube 15, is adapted to be applied to the carrier 17 by sliding movement radially towards the axis of the carrier, with the portion 25 resting on the bore wall of the carrier, and the portion 26 occupying the slot 27, with its periphery flush with the periphery of the carrier 17. The junction of the portions 25 and 26 of the ring affords shoulders at 28 adapted to abut the shoulders at the ends of the slot 27, to insure accurate positioning of the sight. As a result of this construction all of the parts are snugly fitted, will produce unnoticeable wear through continued use and such parts are held in position through the friction between the carrier 17 and tube 15 and the action of the set screw 22 against the lug 21.

As shown in Figures 2, 3, 4, and 5, the sight across its opening or bore has a horizontal wire 29 of metal fastened in place in any suitable manner, which carries a pair of beads 30, also usually of metal, equidistantly spaced on opposite sides of the longitudinal axis of the sight.

A modified form of sight may be used as suggested in Figures 6 and 7 wherein a disk of celluloid or other transparent material at 31 is fastened in any desired manner within the ring 24. Such disk 31 has a central opening 32 therethrough, and on a horizontal line passing through its longitudinal axis, beads 33, preferably of metal are equidistantly positioned from that axis.

The same positioning of beads of metal or the like 34, in Figure 8, is effected as in the form of Figures 5 and 6, where the thinner portion of the sight is inwardly thickened as at 35,

35

40

45

50

and has studs 36 rising therefrom and carrying the beads 34.

I prefer to employ a sight using a pair of beads as described at 30, 33 and 34 hence in connection with the bull's eye, the appearance of three beads in a row is afforded with the bull's eye seen exactly between the two beads, enabling the marksman to shoot absolutely straight as he has an exceptionally clear and open view. The sight aids the marksman in keeping the gun from being held on a cant. Obviously, any other form of sight with a different arrangement of beads may be employed according to the effectiveness or individual desires in view.

It will be noted that the carrier tube 17 extends slightly beyond the mounting body or tube 15 thereof as best shown in Figures 1 and 2. The device is thus sufficiently long to shut out the rays of the sun from the sight even when shooting toward the west as the sun is getting low.

The present sight is a boon for those whose eyesight is failing, although obviously it is adapted for general use with maximum efficiency.

Various changes may be resorted to provided they fall within the spirit and scope of the invention.

I claim as my invention:—

30 1. A sight of the class described comprising a tubular carrier, having a slot extending peripherally through its wall, a sight member comprising a ring having a portion of said ring resting on the bore wall of the carrier and a portion of said ring occupying said slot flush with the exterior of the carrier, and a mounting member having a tubular portion in which said carrier is telescoped with a portion overlapping said ring.

40 2. A sight of the class described comprising a tubular carrier, having a slot extending peripherally through its wall, a sight member comprising a ring having a portion of said ring resting on the bore wall of the carrier and a portion of said ring occupying said slot flush with the exterior of the carrier, a mounting member having a tubular portion in which said carrier is telescoped with a portion overlapping said ring, and a manipulating flange on one end of said carrier tube abutting said tubular portion.

50 3. A sight of the class described having a carrier tube provided with a circumferential slot extending through its wall, a sight member comprising a ring, said ring having portions of dif-

ferent widths, said portion of narrower width resting on the bore wall of the carrier tube, the other portion occupying said slot of the carrier tube and having its outer periphery flush with the tube, a mounting body having a tubular portion in which the carrier tube is telescoped, and interfitting means between said carrier tube and mounting body for retaining the tube in position in said carrier.

4. A sight of the class described having a carrier tube provided with a circumferential slot extending through its wall, a sight member comprising a ring, said ring having portions of different widths, said portion of narrower width resting on the bore wall of the carrier tube, the other portion occupying said slot of the carrier tube and having its outer periphery flush with the tube, a mounting body having a tubular portion in which the carrier tube is telescoped, and interfitting means between said carrier tube and mounting body for retaining the tube in position in said carrier comprising a lug on the carrier tube, the mounting body having a slot occupied by said lug, and means on the mounting body securing said lug in said slot. 25

5. A sight of the class described having a carrier tube provided with a circumferential slot extending through its wall, a sight member comprising a ring, said ring having portions of different widths, said portion of narrower width resting on the bore wall of the carrier tube, the other portion occupying said slot of the carrier tube and having its outer periphery flush with the tube, a mounting body having a tubular portion in which the carrier tube is telescoped, and interfitting means between said carrier tube and mounting body for retaining the tube in position in said carrier comprising a lug on the carrier tube, the mounting body having a slot occupied by said lug and means on the mounting body securing said lug in said slot, and a plurality of sight beads positioned in said ring on a diametric line and equidistantly on opposite sides of the longitudinal axis. 35 40 45

6. A sight of the class described comprising a ring, bead means within the ring, said ring consisting of circumferential portions differing in width from each other, said bead means comprising a pair of beads in radial alignment and each equidistantly spaced from the longitudinal axis of the ring and relatively fine supporting means for the beads extending inwardly from the wall of the ring. 50
